UNITED STATES PATENT OFFICE.

FRANK B. SMITH, OF PHILADELPHIA, PENNSYLVANIA, ASSIGNOR TO THE BARBER ASPHALT PAVING COMPANY, OF PHILADELPHIA, PENNSYLVANIA, A CORPORATION OF WEST VIRGINIA.

PAVING MACHINERY.

No. 853,131.

Specification of Letters Patent.

Patented May 7, 1907.

Application filed January 31, 1906. Serial No. 298,761.

To all whom it may concern:

Be it known that I, FRANK B. SMITH, of Philadelphia, in the State of Pennsylvania, have invented certain new and useful Improvements in Paving Machinery, whereof the following is a specification, reference being had to the accompanying drawings.

My invention relates to improvements in apparatus for preparing the mixtures of asphalt and sand which are commonly used for paving purposes, and is more specifically adapted (although not limited) to that type of apparatus known as portable or railway plants wherein all the required apparatus is permanently and operatively mounted upon a suitable car for transportation from city to city. In a prior patent obtained by myself in conjunction with Henry R. Kasson, No. 783,146, dated February 21st, 1905, I show and claim such a portable asphalt plant. In all such portable plants a problem is presented in finding a suitable location for the screen and hot storage bin; the necessary limitations of a railroad plant preventing them from conveniently occupying the elevated position commonly assigned to them in permanent plants.

My present invention consists in certain improvements in such a plant as generally described in the above referred to patent, and has reference more specifically to a novel position and operation of the screen, the employment of a charging spout suspended from the hot sand elevator, the interposition of an overflow spout, the arrangement of the storage bin, and its preferably extensible character, and the employment of a separate gasoline engine for the purpose of operating the plant.

In the accompanying drawings, I have illustrated and will now describe a preferred form of construction in which I embody my present improvements.

In said drawings, Figure I, is a plan view, and Fig. II, a side elevation of the parts of a portable asphalt plant to which my invention relates. Fig. III, is a detailed view of the mechanism for extending the elevator. Fig. IV, is a sectional view of the extensible or telescopic sand reservoir.

The mechanism shown is all mounted upon the floor 1, of an open car body and near the center thereof. On one side of this appara-

tus there is erected the usual asphalt tank and upon the other side the usual sand heating apparatus, but these being of well known construction I have not shown them in the drawings of this case and will not here describe them. They may be used as shown in the prior patent to myself and Kasson above referred to.

From the sand heater or drum the sand is delivered by way of a spout 2, (Fig. II), to a rotatory screen 3, situated close to the floor of the car. This screen is in no wise connected with the sand drums, but is mounted in a separate covered cradle, and is driven independently of the drums, being thus protected against the destructive effects of the products of combustion sent through the drums for the purpose of heating them. Below this screen and let into the floor of the car are two small hoppers of which the larger one 4, receives the screened heated sand, while the smaller one 5, receives the tailings and discharges them upon the ground through a spout 6. In close proximity to the sand screen is the elevator frame 7, containing the extensible upper portion 8. Within this frame is mounted an endless bucket chain 9, with the customary driving connections.

The lower end of the elevator frame is let within and dips below the frame of the car. It is provided with an opening 10, through which the hot sand from the hopper 4, is admitted to the lower end of the elevator frame to be caught and raised by the buckets. The bottom of the elevator frame is provided with a sliding gate 11.

The top of the elevator frame is provided with two spouts of which the uppermost 12, is a charging spout of considerable length and proportions provided with a gate 13, at its lower end. This spout is capable when the gate is closed of holding within itself more than the nine cubic feet of sand which in customary usage forms one charge for the sand box. Below the charging spout is the overflow spout 14, opening from the lower side of the angle between the charging spout and the elevator frame, in such position that as soon as the charging spout has been filled, all further sand delivered to it by the elevator must pass into the overflow spout. As will be noticed in Fig. I, the two spouts are divergently directed so that the charging

spout 12, discharges directly above the measuring box 15, which is of the usual construction to contain nine cubic feet of sand. On the other hand the overflow spout 14, discharges into a hot sand reservoir 16.

The charging spout 12, by reason of its size, performs to some extent, the function heretofore accomplished by the hot sand storage bin, usually separately supported in an elevated position over the mixing platform; but it will be noted that in this case, no such structure is employed, but merely an appendage of the extensible portion of the hot sand elevator to which alone the charging spout is attached and by which it is supported. In this way I have been able to secure the practical advantages of the elevated hot sand storage bin, while doing away with the disadvantages of a cumbrous elevated structure upon the railroad plant which must be removed whenever the car is placed in transportation.

The measuring box 15, is provided with means for emptying its contents into the mixer 18.

19, is the pipe by which asphalt is fed into the mixer from the asphalt tank.

In the operation, as distinguished from the transportation of the plant, the sand box and mixer are projected from the side of the car, being mounted on a truck 20, with rollers 21, running on the removable I beams 23. Thus the mixer, which empties at the bottom may discharge its contents directly into a wagon extending beneath, and the mixture be carried to the work.

The hot sand reservoir 16, has a sloping bottom 24, and is provided at its lower end with a spout 49, which returns heated sand from the reservoir directly to the bottom of the elevator frame where it is again fed to the buckets.

For the operation of the machine I provide a compact gasoline engine 25, mounted along side of the hot sand reservoir. The shaft 26, of this engine is geared to a complementary shaft 27. A sprocket chain 28, driven from the shaft 27, operates the geared shafts 29, and 30, which carry the stirring blades mounted within the mixer 18, which is shown of the ordinary twin-plug variety. The sprocket chain 31, driven from the shaft 27, serves to drive the rotary screen 3. The shaft 26, drives the sprocket chain 32, by which is operated the blower 33, of the sand drums. The shaft 27, is connected by bevel drums. The shaft 27, is connected by bevel gears 38, 38, to the transverse shaft 39, which drives a sprocket chain 40, by which the elevator is operated. The shaft 39, is connected by sprocket chain 41, with a short twin-shaft 42, provided with bevel gear 43, by which the sand drums are operated.

In Fig. III, there is shown in detail the mechanism employed for extending the ele-

vator prior to the operation of the plant. As heretofore explained this elevator is telescopic and when the car is traveling and the plant not in use, its upper portion is allowed to descend within the lower portion, the overflow spout 14, being unbolted and removed to permit of this descent. To extend the telescopic end a small winch 44, is permanently attached to the side of the elevator the rod or cord of which 45, passes around the rollers 46, and 47, and is then attached to the lower end of the upper extensible member of the elevator frame.

In Fig. IV, there is disclosed in section the construction of the hot sand reservoir whereby it is rendered telescopic. When the plant is in motion it is necessary for the mixer and measuring box to be moved from their overhanging position and run onto the body of the car, directly over the sand reservoir. When this has been done the projecting extremities of the beams 23, are unbolted and removed. But on account of its size, the sand reservoir 16, would forbid this motion, were it not capable of being telescoped. Accordingly, it is made as shown in Fig. IV, in three sections, each of smaller size than the other and capable of being received one within the other. When thus depressed, the height of the sand reservoir is such as to permit the sliding of the sand box and mixer directly over it.

Having thus specified the parts, and preferred construction of my invention I will now explain its operation and advantages. In the operation of these cars it is usually essential that the feeding of heated sand from the drum should be continuous, otherwise a uniform temperature for the sand cannot be secured. On the other hand, owing to the irregular movements of the carts by which the asphalt mixture is transported from the plant to the streets of the city where it is to be laid, the removal of the mixture from the plant is necessarily more or less intermittent. By my improvements the heated sand which is continuously delivered from the drum, after being screened, is as continuously raised by the elevator and delivered into the charging spout 12. This charging spout has sufficient capacity to more than fill the measuring box 15, into which it discharges, so that when the carts are coming in rapidly and the plant working to its full extent, the measuring box can be rapidly and successively filled with the desired nine cubic feet of sand. If the transporting wagons do not arrive with sufficient regularity the sand which is raised by the elevator overflows from the charging spout into the overflow spout 14, by which it is delivered into the hot sand reservoir 16, the capacity of which is great enough to provide a very considerable storage of hot sand, which when the plant is running rapidly may be used by

feeding the sand from its bottom by the spout 49, into the elevator in order to temporarily increase the supply to the elevator and consequently to the charging spout. 5 This large hot sand reservoir is further useful in regulating the temperature of the sand, for the reservoir, although of course maintaining the sand at a high temperature for many hours, will as a rule contain cooler sand 10 than that which is fed directly from the drum. If therefore, the sand from the drum is a little too hot a proper admixture of cooler sand from the reservoir 16, is permitted, whereby the required temperature may be 15 secured with greater precision.

Having thus described my invention, I claim:

1. In an asphalt plant, the combination of the elevator, and measuring box, with provision of a charging spout for the elevator discharging into the measuring box; a hot sand reservoir; and an overflow spout for the elevator discharging into the hot sand reservoir, substantially as set forth. 20
2. In an asphalt plant, the combination of a sand elevator; means for feeding heated sand to the bottom of the elevator; a charging spout at the top of the elevator, of sufficient capacity to contain more than nine cubic 25 feet of sand and provided with a gate at its lower end; and an overflow spout at the top of the elevator opening from near the top of the charging spout so as to receive sand only when the charging spout is filled, substantially as set forth. 30
3. In an asphalt plant, the combination of a sand elevator with a charging spout at its top; means for supplying heated sand thereto; a sand measuring box into which the 40 charging spout of the elevator empties; an overflow spout leading from the upper end of the charging spout and diverging in direction therefrom; a hot sand reservoir into which the overflow spout discharges; and 45 means for returning the sand from the reservoir to the bottom of the elevator, substantially as set forth.
4. In a portable asphalt plant, the combination of a car, means for continuously heating and feeding sand; a rotary screen cradled independently of the heating apparatus near the floor of the car; a sand elevator running from below the surface of the car to a higher

point; and a hopper below the screen discharging continuously into the bottom of the 55 elevator, substantially as set forth.

5. In a portable asphalt plant, the combination of a car, a sand elevator, a sand reservoir, and a measuring box, the measuring box when in use being alongside of the sand 60 reservoir; means for diverting the sand from the top of the elevator either to the measuring box or to the sand reservoir; the sand reservoir being upwardly extensible whereby its capacity may be enlarged when in use, 65 while when the car is being transported it may be collapsed so as to permit the sand measuring box to be carried over it, substantially as set forth.

6. In a portable asphalt plant, the combination of a car, a sand measuring box and mixer mounted upon a laterally moving truck; means whereby when the plant is in operation this truck with its measuring box and mixer may be projected laterally from the 75 car to facilitate the discharge therefrom; an upwardly extensible sand reservoir which when in use is enlarged in capacity by its upward extension, and situated alongside of the sand measuring box and mixer as projected 80 from the car, while when the car is being transported said reservoir may be collapsed to permit the withdrawal of the truck carrying the sand measuring box and mixer from the side of the car to a position over the collapsed reservoir, substantially as set forth. 85

7. In a portable asphalt plant, the combination of a car, a sand elevator; a sand drum at one side thereof, whereby heated sand is continuously delivered to the bottom of the 90 elevator; a sand screen; an asphalt tank at the other side of the elevator; a sand reservoir into which the elevator discharges; a sand measuring box and mixer which when in use is mounted near the sand reservoir, 95 and, a gasoline engine mounted near the sand reservoir whereby the drum, screen, elevator and mixer are operated, substantially as set forth.

In testimony whereof, I have hereunto signed my name, at Philadelphia, Pennsylvania, this 26th day of January 1906.

FRANK B. SMITH.
